(57) **CLAIM**

The ornamental design for a set of shredder, as shown and described.

DESCRIPTION

FIG. 1 is a top perspective view of a set of shredder, showing my new design.

FIG. 2 is bottom perspective view thereof.

FIG. 3 is a front view thereof.

FIG. 4 is a rear view thereof.

FIG. 5 is a left side view thereof.

FIG. 6 is a right side view thereof.

FIG. 7 is a top view thereof.

FIG. 8 is a bottom view thereof; and,

FIG. 9 is a top perspective view thereof, shown in assembled condition.

The broken lines shown in the drawings represent portions of the set of shredder that form no part of the claimed design.

1 Claim, 9 Drawing Sheets
